UNITED STATES PATENT OFFICE.

PAUL B. MURPHY, OF NYACK, NEW YORK, ASSIGNOR TO WESTERN ELECTRIC COMPANY, INCORPORATED, OF NEW YORK, N. Y., A CORPORATION OF NEW YORK.

SIGNALING SYSTEM.

Application filed November 10, 1921. Serial No. 514,203.

To all whom it may concern:

Be it known that I, PAUL B. MURPHY, a citizen of the United States, residing at Nyack, in the county of Rockland, State of New York, have invented certain new and useful Improvements in Signaling Systems, of which the following is a full, clear, concise, and exact description.

This invention relates to signaling systems and more particularly to a method of and means for signaling over transmission lines.

One of the objects of this invention is to provide improved means for signaling over long transmission lines.

Another object is to provide improved means for signaling over transmission lines designed primarily to efficiently transmit message currents.

Another object is to provide, in a system of this nature, improved means for preventing mutual interference between ringing and message currents.

Another object is to provide for two-way transmission in a system of this nature.

To attain the objects of this invention each end of the transmission line is provided with a sending and a receiving circuit. The sending circuit comprises means for producing and transmitting oscillations of a single audible frequency interrupted at a low frequency rate. The receiving circuit comprises means for rectifying and translating the modified oscillations into a signal. The receiving circuit is also provided with a tuned circuit so as to exclude all audible frequency currents except that current having the frequency selected for signaling purposes. The receiving circuit is further provided with means which responds only to an audible frequency current modulated or interrupted at a predetermined rate, so that the component of speech currents present

on the line, during conversation, of the particular frequency selected for signaling, will not cause the actuation of the signaling device. The receiving circuit is also provided with means for preventing outgoing voice frequency currents from affecting the receiving circuit at the outgoing station.

It is believed that the invention will be better understood from the following description having reference to the accompanying drawing showing, in diagrammatic

form, a specific embodiment of the invention.

In the drawing reference character L designates a telephone transmission line extending between stations A and B. The rectangles R' and R indicate that any well known voice repeating apparatus may be inserted in the line. It is to be understood that the line L may be composited or simplexied, but since such arrangements are old and well known in the art, it is not thought advisable to complicate the drawing with such a showing. Stations A and B are equipped with like apparatus, the equipment for station B being completely shown, and for station A, in part only, in order to avoid unnecessarily complicating the drawing. Like apparatus is designated with like reference characters except that at the station A primes are added to the reference characters. Cord circuits C' and C are for the purposes of extending connections over the transmission lines and only the apparatus which forms a part of this invention is shown. It will be understood that any suitable cord circuit for the traffic conditions desired may be employed embodying the elements shown. Signals 14' and 14 are actuated in response to an incoming call for their respective stations. Only sufficient apparatus for the sending and receiving circuits is shown at station A to illustrate how the station A may call station B, it being understood that the remaining apparatus is a duplicate of that shown at station B. The apparatus shown to the right of and below the dotted line comprises a sending and receiving circuit for station B. The sending circuit includes a source of oscillations O. While a generator is herein shown as a source of oscillations, it will be understood that any other suitable means may be employed.

By means of a generator S and a relay 21, the oscillations are modified in a predetermined manner. In the following description the oscillations will be described as having a frequency of 950 cycles per second and the current of the source S as having a frequency of 16 cycles per second. It is to be understood, however, that these values are simply illustrative and the invention is not limited to the employment of these frequencies. The receiving circuit in-

cludes a tuned circuit, a tube V of the well known type and a chain of relays including relay 29. The tuned circuit includes a condenser 24 and a coil 25 and is preferably so designed as to exclude all voice frequency and alternating currents except that current having the frequency selected for signaling. In order to prevent undue loss to voice currents on the line, the impedance of the circuit consisting of the line winding of transformer 22 and condenser 23 is made high as compared to the impedance of the line. To accomplish proper tuning the impedance is stepped down through coil 22 to the tuned circuit. Coil 26 is so designed that the windings toward the tuned circuit match the impedance of the tuned circuit and the secondary winding effects a step-up of the impedance so as to match the impedance of the grid of tube V. The incoming modified audible frequency signaling current is rectified by means of the tube V. The relay 29 responds to the alternating current which is induced into the secondary of coil 28, due to the rectified groups of modulated audible frequency current flowing through its primary, to control relays 33, 44 and 45 of the chain of relays, which relays in turn control the application of 16 cycle current from the source 46 which current actuates the signaling device 14.

It is believed that the invention may be more fully comprehended from the following detailed description of the operation of the system.

Assuming that it is desired to signal station B from station A over the transmission line L, the operator at station A will insert plug 10' of the link circuit C' into the jack 11', whereupon the signaling device 14' is disconnected from the transmission line. The operator may then actuate the key K' connecting the source 5' of low frequency ringing current to the line, causing the energization of the relay 60' at the sending station. The path for the energization of 60' may be traced as follows, from source of ringing current 5', through the upper contacts of key K', tips of plug 10' and jack 11', coil 49', condenser 47', outer contacts of relay 45', winding of relay 60', inner contacts of relay 45', coil 48', rings of jack 11' and plug 10', lower normal contacts of key K' to source of ringing current 5'. Relay 60', in operating, completes, through its contacts, an obvious circuit for relay 20'. Relay 20', in operating, connects, through its left-hand contacts, the source of oscillations O' to the transmission line. Through the right-hand contacts of relay 20', relay 21' is connected in circuit with the source of low frequency ringing current S'. The generator S' generates alternating current of preferably 16 to 20 cycles per second, and each time relay 21' ener-

gizes, oscillations from the source O' will be transmitted over the line L through the repeaters R' and R. The characteristics of the transmission line, containing repeaters R' and R are such that voice frequency currents only are transmitted efficiently, and therefore the low frequency ringing currents from the source 5' are not transmitted to the distant station B when the key K' is actuated.

The modified voice frequency current from the source O' passes through the contacts of relay 20', the repeaters R' and R, right-hand contacts of relay 20, the primary windings of repeating coil 22 and condenser 23. The current passing through the primary windings of coil 22 induces a corresponding current in the secondary winding. The circuit including the secondary winding of coil 22, condenser 24 and coil 25, and the primary of repeating coil 26 is preferably a tuned circuit of relatively low impedance as heretofore stated. Current through the primary winding of coil 26 induces a corresponding current in the secondary winding thereof. The secondary winding of coil 26 is preferably designed so as to have an impedance equaling the impedance of the grid 41 of the tube V. The modified oscillations are rectified by means of the tube V and the rectified current passes through the primary winding of coil 28. The condenser 27 serves as a by-pass for the oscillation components of a rectified group as well as to tune the high side of the transformer 28 to the 16 cycles. The impedance of the primary winding of coil 28, in conjunction with condenser 27, is approximately equal to the impedance of the plate 42 of the tube V. The rectified current passing through the primary winding of coil 28 induces an alternating current in the well known manner into the secondary winding of this coil to cause the operation of alternating current relay 29. Relay 29 is preferably so designed, that its impedance equals the impedance of the secondary of coil 28. As relay 29 receives the current produced by the rectifier V, the armature thereof will rapidly close the upper and lower contacts alternately, each at the rate of 16 times per second in accordance with the frequency of the 16 cycle ringing current generator S'.

When the upper contacts of relay 29 are closed the condenser 32 will be charged by the battery B due to current flowing over the following path: from positive pole of battery B, resistance 31, winding of relay 33, condenser 32, upper contacts of relay 29 to minus pole of battery B. Although current at this time also flows through the resistance element 30 and the upper contacts of relay 29, thereby setting up a drop of potential across the resistance element 30 which will

aid the charging of the condenser 32, the main charge for this condenser is obtained over the circuit just traced. As soon as the upper contacts of relay 29 are opened, a condenser 32 commences to discharge due to its being short circuited over the series path including the winding of relay 33 and resistances 31 and 30. If the condenser 32 is not fully discharged over the short circuit path during the time that the contacts are open, it will be fully discharged when the lower contacts of relay 29 are closed because a charge will be started in the opposite direction which will be completed due to the current flowing from positive pole of battery, through resistance 30, condenser 32, relay 33, lower contacts of relay 29 to minus pole of battery B. The resistances 30 and 31 thus start the discharge of the condenser 32 as soon as the associated upper and lower contacts of relay 29 are opened resulting in the current through relay 33 assuming a wave form that is substantially sinusoidal. This operation continues as long as the modified oscillations are applied to the transmission line. Relay 33 is thereupon energized and upon energization short-circuits relay 44 which is normally operated over an obvious circuit including resistance 50, allowing said relay 44 to release. Relay 44, in releasing, completes a circuit for slow-to-operate relay 45. The circuit of the chain of relays including relays 29, 33, 44 and 45, is so designed that their operation will not be completed except when the rate of operation of relay 29 is between 16 and 20 cycles. For example, relay 33 is so designed that it must have current of 16 to 20 cycles in sufficient quantity to hold it operated and if relay 29 is vibrated at a greater or lower rate sufficient current will not flow through relay 33 to hold it continuously operated. Continuous operation of relay 33 is necessary before relay 44 releases. Relay 45, in operating, connects 16 cycle current from the source 46 to the transmission line to actuate the drop 14.

This 16 cycle current is excluded from the receiving circuit at station A due to the characteristics of the line L and its associated apparatus which may or may not include the repeaters R and R'. It is excluded from the receiving circuit at station B due to the fact that the receiving circuit thereat is tuned to exclude all currents except that of the signaling frequency or approximately 950 cycles.

As soon as the operator at station A restores key K' to normal, all apparatus except signaling device 14 is restored to normal. The operator at station B noting the signal produced by the device 14, may insert plug 10 into jack 11 and complete the connection in any well known manner. If the operator at station B desires to signal

the operator at station A, key K is actuated to apply current from the source 5 to the line, causing the actuation of relay 60, which in operating actuates relay 20, which in turn causes the modulated oscillations from the source O to be connected to the line L. The receiving circuit at station A (not shown) then responds in a manner similar to that heretofore described for station B to cause the operation of signal 14'. It will be readily apparent to those skilled in the art that any suitable signaling device (not shown) may be associated with the cord circuit C' so that if station B desires to signal station A, while the plugs 10 and 10' are in their respective jacks, a signaling device (not shown) in the cord circuit C' may be actuated to apprise the operator at station A of such a call.

What is claimed is:

1. The method of transmitting ringing currents in such a form that they are effectively transmitted by apparatus designed to efficiently transmit speech currents, which comprises interrupting a single speech frequency current at a lower frequency rate and transmitting and rectifying said interrupted current and translating the rectified current into a signal. 85

2. The method of transmitting ringing currents in a form such that they are effectively transmitted by apparatus designed to efficiently transmit message currents, and of preventing mutual interference of the ringing and message currents, which comprises modifying a single speech frequency current at a lower frequency rate and transmitting and selectively translating into a signal the ringing currents to the exclusion of the message currents. 100

3. The method of signaling which comprises modifying a single audible frequency current at the rate of another frequency, transmitting the modified current, rectifying the same, translating the rectified current into an alternating current of a frequency corresponding to the modifying frequency and translating the alternating current into a signal. 110

4. The method of signaling which comprises modifying a single frequency essential in speech at a lower frequency rate, transmitting the modified current, rectifying the modified current, and translating the rectified current into a signal. 115

5. In a signaling system, a transmission line, a source of audible frequency current, means for interrupting current from said source at a uniform rate and applying it to said line, a signal, and means including a rectifying device and responsive to said interrupted current for actuating said signal. 125

6. In a signaling system, a transmission line, a source of audible frequency current, means for modifying current from said

- source at a definite rate and applying it to said line, a signal and means including devices responsive to said modified current for rectifying the same, producing an alternating current from said rectified current, said alternating current having a frequency equal to the rate of modification and for actuating said signal in response to said alternating current.
10. 7. In a signaling system, a transmission line over which voice frequency currents may be efficiently transmitted, a source of current having a frequency essential in speech, a source of ringing current, means responsive to said ringing current for interrupting current from said first mentioned source at the frequency of said ringing current, a signal, and means associated with said transmission line responsive to said interrupted current from said first mentioned source to actuate said signal.
15. 8. In a signaling system, a transmission line over which voice frequency currents may be efficiently transmitted, extending between a sending and a receiving station, a source of oscillations, means at the sending station for applying oscillations from said source at fixed intervals to the transmission line, a signal, and means at the receiving station responsive to the applied oscillations for actuating said signal.
20. 9. A signaling system comprising a transmitting station, a distant station having signal apparatus, a line connecting said stations, a source of audible frequency current at said transmitting station, means for applying current from said source to said line at fixed intervals, and means at said distant station including a chain of relays responsive only to said audible frequency current applied at fixed intervals to actuate said signal apparatus.
25. 10. In a signaling system, a line, a source of audible frequency current, means to interrupt current from said source at a predetermined rate and apply it to said line, a signal, and means including a relay responsive to said current only when interrupted at the predetermined rate to actuate said signal.
30. 11. In a signaling system a two-way transmission line designed to efficiently transmit voice currents, a source of audible frequency current at each end of said line, means at each end of said line for interrupting current from said source at a fixed rate and applying it to the line, a signal at each end of the line, means at each end of the line responsive to the interrupted current transmitted from the opposite end to actuate the signal, and means at each end of the line for preventing outgoing audible frequency currents from affecting the signal at the outgoing end.
35. 12. In a signaling system, a transmission line, a relay, two contacts therefor, an armature for said relay, a source of oscillations, means for modulating said oscillations and applying them to said line to actuate said relay to alternately make said contacts, a condenser, a circuit for charging said condenser when said armature makes either contact and for discharging said condenser when said armature is alternating between its contacts, an electromagnet actuated by the charging and discharging of said condenser, and a signal controlled by said electromagnet.
40. 13. In a signaling system, a relay having an armature, two contacts for said armature, means for vibrating said armature, a direct current source connected to said armature, a resistance connected to each of said contacts, a condenser, circuit connections whereby said condenser charges each time said armature makes with one of said contacts, and discharges during the vibration between contacts, an electromagnet actuated by the charging and discharging of said condenser, and a signal controlled by said electromagnet.
45. 14. In a signaling system, a relay having an armature vibrating in response to periodically varying current, contacts between which said armature vibrates, a direct current source connected to said armature, a resistance connected to each of said contacts, a circuit completed through said armature and one of said resistances each time said armature vibrates, a condenser charged at each completion of said circuit, a conductive path around said condenser for discharging it, an electromagnet actuated by the charging and discharging of said condenser, and a signal controlled by said electromagnet.
50. 15. In a signaling system, a source of oscillations which are efficiently transmitted by a speech frequency apparatus, means for interrupting said oscillations at a definite rate, a source of lower frequency ringing current, a line, means including relays for controlling the application of the interrupting means to the first mentioned source and for controlling the application of the resulting signaling current to said line, and means including a key for actuating said relay control means from said second mentioned source.
55. 16. In a signaling system, a sending station, a receiving station, a line interconnecting said stations, a ringing current source at said sending station, means for applying current from said source to the originating end of said line, means associated with the originating end of said line and responsive to current from said source for applying current of a frequency in the range of audibility to the terminating end of said line and for modulating the audible frequency

current in accordance with the frequency of the current from said ringing current source, means at the terminating end of said line selectively responsive to the modulated audible frequency current, means for rectifying the modulated current, and means at said receiving station for translating the rectified current into a signal indication.

17. In a signaling system, a sending station, a receiving station, a line interconnecting said stations, a ringing current source at said sending station, means for applying current from said source to the originating end of said line, means associated with the originating end of said line and responsive to current from said source for applying current of a frequency in the range of audibility to the terminating end of said line

and for modulating the audible frequency current in accordance with the frequency of the current from said ringing current source, a circuit at the terminating end of said line tuned to receive the modulated audible frequency current to the exclusion of all other voice frequency currents, means for rectifying the modulated current, electromagnetic means inductively coupled to said rectifying means adapted to operate in accordance with the frequency of the rectified current, and a slow-operating relay controlled thereby for effecting a signal indication at the receiving station.

In witness whereof, I hereunto subscribe my name this 4th day of November A. D., 1921.

PAUL B. MURPHY.
